(57) **CLAIM**

The ornamental design for a baby bib, as shown and described.

DESCRIPTION

FIG. 1 is a front perspective view of a baby bib showing my design;

FIG. 2 is a rear perspective view thereof;

FIG. 3 is a front view thereof;

FIG. 4 is a rear view thereof;

FIG. 5 is a right side view thereof, which is a minor image of the left side view thereof;

FIG. 6 is a top view thereof; and,

FIG. 7 is a bottom view thereof.

The broken lines in FIGS. 1-5 form no part of the claimed design but show an environment in which the design may be used.

1 Claim, 7 Drawing Sheets Fig. 3
